M. MITCHELL,
FASTENER FOR SHUTTLE TIPS,
APPLICATION FILED SEPT. 15, 1919.

1,339,572.

Patented May 11, 1920.

Inventor:
Moorehouse Mitchell

By William Colinton
Attorney

UNITED STATES PATENT OFFICE.

MOOREHOUSE MITCHELL, OF QUEBEC, QUEBEC, CANADA.

FASTENER FOR SHUTTLE-TIPS.

1,339,572.

Specification of Letters Patent. Patented May 11, 1920.

Application filed September 15, 1919. Serial No. 323,865.

To all whom it may concern:

Be it known that I, MOOREHOUSE MITCHELL, a subject of the King of Great Britain, residing at Quebec, Province of Quebec, 5 Canada, have invented certain new and useful Improvements in Fasteners for Shuttle-Tips; and I do hereby declare that the following is a full, clear, and exact description of the invention, such as will enable others 10 skilled in the art to which it appertains to make and use the same.

The present invention relates to loom shuttles and more particularly to the manner of attaching the metallic tips to the 15 ends of shuttles.

Heretofore these metallic tips had been applied to the shuttles in such a manner as to exert an outward pressure upon the wooden body of the shuttle, as they are subjected to knocks and jars when passing 20 through the loom, and this outward pressure has a tendency to split or crack the shuttle.

The purpose of the present invention is to 25 provide a simple and firm connection between the metal tips and the shuttle, so as to overcome the inconveniences heretofore experienced and permit the use of timber in making the shuttles, that has heretofore 30 been wasted.

With this and other objects in view, which will readily appear as the description progresses, the invention consists of the novel features of construction, combination and 35 arrangement of parts hereinafter more fully described, illustrated and claimed.

A preferred embodiment of the invention is shown in the accompanying drawings, in which:

40 Figure 1 is a detailed plan view of one end of a shuttle having a metallic tip applied thereto;

Fig. 2 is a large detailed sectional view showing the connection between the tip and 45 the shuttle;

Fig. 3 is a sectional view showing the tip, a portion of the shuttle and their connection disassembled; and,

Fig. 4 is a vertical transverse section taken 50 on the line 4-4 of Fig. 2.

Referring now more particularly to the accompanying drawings wherein like and corresponding parts are designated by similar reference characters throughout the several views,

In the manufacture of loom shuttles, great

difficulty is experienced in properly preparing wood for the shuttles, as the end pressure on the shuttle as it passes through the loom is so great that it will tend to 60 crack or split the same. To increase the life of the shuttle heretofore, the heart of the wood has not been used, and the top portions of tree trunks as well as their branches have been left to waste. In the present invention I have provided a means for fastening the metallic tips to the shuttles which 65 will permit the tips to take up the end pressures or knocks upon the shuttle, and which will prevent the body of the shuttle from 70 cracking or splitting thereby greatly increasing its life.

In the drawings, the numeral 1 indicates a metallic tip of the ordinary configuration, which is to be applied to the end of a loom 75 shuttle, and this tip has formed therewith a shank consisting of a tapered portion 2 and a cylindrical portion 3. The loom shuttle 4 is substantially of the same general construction as the shuttles now in use, and 80 the tips 1 are to be applied to the ends thereof, as better shown in Fig. 1. Formed within each end of the shuttle is a cylindrical recess 5 which is for the reception of the shank of the tip 1. Adapted to encircle the 85 shank of the tip is a collar 6 having an outer cylindrical periphery and its bore 7 is so reamed as to have a truncated conical configuration, so that its end 8 which is of the smallest diameter extends nearest the tip 90 1, and the opposite end of the collar is provided with a relatively sharp or chisel edge 10. In fastening the tip to the shuttle the shank is placed within the recess 5, and this recess 5 is of greater length than that of the shank carried by the tip, as better shown in Fig. 2 of the drawings. By means of a hammer the tip is struck to force the sharpened edge 10 of the collar to bite into the 95 wooden body portion of the shuttle, and a portion of the shuttle is wedged between the inner tapered periphery of the collar and the outer tapered periphery of the shank, thereby securely fastening the tip to the shuttle.

As is well known the pressure encountered 100 at the tip of the shuttle is such that it often causes the splitting of the shuttles and by this device I have overcome this difficulty, as any undue or extraordinary pressure at the shuttle ends will only tend to force the 110 tips 1 inwardly and cause the collars 6 to bite farther into the shuttle ends. In this

manner, pieces of timber containing the heart, which is now waste, may be used, being prepared for drying by boring out the heart, so permitting the wood to shrink 5 without cracking.

Having thus fully described my invention, what I claim as new and desire to secure by Letters Patent is:—

1. The combination with a wooden loom shuttle having a recess formed therein, of a metallic tip, a shank formed with said tip adapted to be seated within said recess and of shorter length than the length of said recess, said shank consisting of a cylindrical 10 portion and a tapered portion, a collar adapted to encircle said shank, said collar having a cylindrical outer periphery and a conical inner periphery, said collar having a relatively sharp edge adapted to be forced 15 within said shuttle whereby a portion of the shuttle will be wedged between the tapered portion of said shank and the tapered inner periphery of said collar substantially as and for the purpose specified.

2. The combination with a wooden loom

shuttle and a metallic tip, a shank formed with said tip, said shank having a tapered peripheral portion converging toward said tip, and means for causing the wood of the loom shuttle to be compressed around said 30 tapered peripheral portion of the shank when the latter is driven into the loom shuttle.

3. The combination with a wooden loom shuttle having a recess formed therein, of a metallic tip, a shank formed with said tip adapted to be seated within said recess, said shank having a cylindrical and a tapered peripheral portion, a collar adapted to be driven in the loom shuttle and surround said 35 tapered peripheral portion of the shank, said collar having a conical inner periphery whereby the wood of the loom shuttle will be compressed around the tapered peripheral portion of said shank substantially as 40 and for the purpose set forth.

In witness whereof I have hereunto set my hand.

MOOREHOUSE MITCHELL.
